CLAIM

The ornamental design for a telephone set, as shown and described.

DESCRIPTION

FIG. 1 is a left side, top and front perspective view of a telephone set showing my new design in cradled status; FIGS. 2 and 3 are respectively front and rear elevational views thereof; FIG. 4 is a left side elevational view thereof, the side opposite being a mirror image thereof; and FIGS. 5 and 6 are respectively top and bottom plan views thereof.

FIG. 3

FIG. 4

FIG. 6
